United States Patent Office

Des. 178,686
Patented Sept. 4, 1956

178,686

ADDRESSING MACHINE

Lester F. Mitchell, Shaker Heights, Ohio, assignor to
Addressograph-Multigraph Corporation, Cleveland,
Ohio, a corporation of Delaware

Application December 20, 1955, Serial No. 39,400

Term of patent 14 years

(Cl. D64—11)

Fig. 1

Fig. 2

Fig. 3

Fig. 4

Fig. 5

Fig. 6

Fig. 1 is a top plan view of an addressing machine showing my new design;

Fig. 2 is a side elevational view thereof;

Fig. 3 is a bottom plan view;

Fig. 4 is an end elevational view looking in the direction of the arrows 4—4 of Fig. 2;

Fig. 5 is an end elevational view looking in the direction of the arrows 5—5 of Fig. 2; and

Fig. 6 is a side perspective view thereof as it would appear in position of use.

I claim:

The ornamental design for an addressing machine, substantially as shown.
